UNITED STATES PATENT OFFICE

LOUIS COCHARD, OF NAPA, CALIFORNIA

LIFEBOAT

Application filed September 3, 1929. Serial No. 389,938.

This invention relates to lifeboats.

It is the principal object of the present invention to generally improve the construction of lifeboats whereby they may be completely enclosed to prevent swamping and be maintained well ventilated without danger of shipping water when in high running seas.

In carrying out the invention into practice I provide a lifeboat hull which is completely decked over so as to prevent the shipping of seas. Ventilators are provided which are so designed that they will admit air to the interior of the boat but will trap any water entering the ventilators and discharge it.

15 One form which the invention may assume is exemplified in the following description and illustrated by way of example in the accompanying drawings, in which:

Figure 1 is a view in side elevation of a 20 lifeboat partially in longitudinal section and disclosing the preferred embodiment of my invention,

Figure 2 is a transverse section taken centrally through the hull,

25 Figure 3 is an enlarged fragmentary view of one of the ventilators,

Figure 4 is a vertical sectional view taken centrally through one of the ventilators on line IV—IV of Figure 3.

30 Referring more particularly to the accompanying drawings, 10 indicates a lifeboat hull of suitable dimensions and lines. At the center of the boat the deck is slightly raised so as to provide sufficient head room in the hull.

35 The space surrounding the raised deck is of course decked over so that the entire hull will be decked in to prevent shipping of any water when the boat is operated in high running seas.

40 For the purpose of gaining entrance to the boat the raised deck portion is provided with a hatchway 11 fitted with a hinged hatch cover 12. A ladder 14 is provided so that persons may enter or exit from the boat 45 through the hatch 11.

The boat here disclosed may be propelled in any desired manner but I prefer to provide a power plant 15 which, in this instance, is shown as an internal combustion engine. The 50 exhaust pipe 16 of the engine extends rear-

wardly through the stern of the boat. The power plant 15 drives the usual propeller 13 at the stern.

I have shown an ordinary type of rudder 17 operated by a tiller 18. It is obvious that 55 I may provide controls for the rudder 17 which may be manipulated from the interior of the boat without departing from my invention.

Due to the fact that the hull is completely 60 enclosed it is necessary to provide means for adequately ventilating the interior of the boat. For this purpose I provide a plurality of ventilators 18 having cowls 19 revolvably projecting from the raised deck. These cowls 65 19 are mounted on the top of air conduits 20 which extend through the raised deck and which are connected at their lower ends to closed drums 21. Overboard discharge pipes 22 are connected at their upper ends to the 70 bottom of the drums and their lower ends extend through the hull of the boat at the bottom thereof below the water-line.

Extending from the horizontal axis of each drum 21 is an air inlet pipe 23 which extends 75 co-axially and then vertically. The outer end of this air inlet pipe 23 is open so that air may be discharged downwardly through the cowl thence into the drum 21 and into the boat through the pipe 23. The air inlet pipe 80 23 is revolvably connected to the drum 21 and is fitted with a depending pendulum or counterweight 24. The purpose of this pendulum or counterweight 24 is to maintain the pipe 23 in a vertical position regardless of 85 the disposition of the pipes 20 and 22. In other words, should the boat completely overturn the counterweight 24 would seek a lower position by gravity and maintain the pipe 23 vertically above the water line so that water 90 entering the pipe 20 through the cowl 19 would only rise to the water-line and as the outlet 23 is above the water-line the water would not enter the boat.

In such a case air would enter pipes 22 95 and pass into the boat through the drum and through the pipe 23.

It is also seen that by the position of the revolvable air inlet pipes 23 and their weights 24 that when the boat is rolling the pipes 23 100

will be maintained above the water-line so as to prevent the entrance of water to the hull. Should water enter the cowls 19 when the boat is in an upright position it will be discharged directly through the drum and through the pipe 22.

In operation of the boat it is intended that it be carried and launched in the same manner as the usual lifeboat. In case it is necessary to use the boat the passengers are lowered into the boat through the hatchway 11 and thereafter the hatchway is tightly clamped shut. Any water passing over the lifeboat after it is launched can not gain entrance into the interior of the boat due to the fact that it is completely decked over and any water discharging into the cowls 19 will be automatically discharged through the pipe 22 as the entrances of the pipes 23 are above the water-line, the water will not pass into the hull.

From the foregoing it is obvious that I have provided a lifeboat which is so constructed that it will not ship water but which at the same time will be maintained well ventilated.

While I have shown the preferred form of my invention it is to be understood that various changes in its construction may be made by those skilled in the art without departing from the spirit of the invention as defined in the appended claims.

Having thus described my invention, what I claim and desire to secure by Letters Patent is—

1. A lifeboat comprising a hull, said hull being completely decked over, a drum arranged within the hull, a vertical pipe extending from the drum through the deck, a cowl fitted to the upper end of said pipe exterior of the hull, conduit extending from the bottom of the drum through the bottom of the hull, an air inlet pipe connected to the drum and having an open end disposed within the hull above the water-line, said air inlet pipe being revolvably connected to the drum, and means for constantly maintaining said pipe in its uppermost position.

2. A lifeboat comprising a hull, said hull being completely decked over, a drum arranged within the hull, a vertical pipe extending from the drum through the deck, a cowl fitted to the upper end of said pipe exterior of the hull, conduit extending from the bottom of the drum through the bottom of the hull, an air inlet pipe connected to the drum and having an open end disposed within the hull above the water-line, said air inlet pipe extending co-axially from the drum and then vertically in the hull, said air inlet pipe being rotatably connected to the drum, and a counterweight fixed to the air inlet pipe and depending from the same and adapted to maintain the same in a vertical

position regardless of the movement of the boat about its longitudinal axis.

3. A lifeboat comprising a hull, said hull being completely decked over, a drum arranged within the hull with its axis horizontally disposed, a vertically disposed air conduit connected at its lower end to the top of the drum and communicating with the interior thereof, the upper end of said conduit projecting through the deck and being fitted at its upper end to a cowl, substantially vertically arranged discharge conduits connected at their upper ends to the bottom of the drum and communicating with the interior thereof, the lower ends of said pipes projected through the bottom of the hull, an air inlet pipe rotatably connected at one end to the drum concentrically to the longitudinal axis thereof, said air inlet pipe being adapted to revolve about a horizontal axis parallel to the longitudinal axis of the hull, said air inlet pipe extending co-axially of the drum and vertically with its outer end disposed above the water-line of the hull and a weight fixed to said pipe and depending therefrom whereby the outer end of said pipe will be maintained in its vertical position regardless of the disposition of the drum, the inlet and discharge conduits.
